CLAIM

The ornamental design for a transcutaneous electrical nerve stimulation device, as shown and described.

DESCRIPTION

FIG. 1 is a top right perspective view of a transcutaneous electrical nerve stimulation device showing our new design; FIG. 2 is a top left perspective view of the transcutaneous electrical nerve stimulation device;

FIG. 3 is a front view of the transcutaneous electrical nerve stimulation device in elevation, taken from the frame of reference of FIG. 1;

FIG. 4 is a rear view of the transcutaneous electrical nerve stimulation device in elevation, taken from the frame of reference of FIG. 1;

FIG. 5 is a right side view, in elevation of the transcutaneous electrical nerve stimulation device in elevation, taken from the frame of reference of FIG. 1;

FIG. 6 is a left side view, in elevation of the transcutaneous electrical nerve stimulation device in elevation, taken from the frame of reference of FIG. 1;

FIG. 7 is a top view of the transcutaneous electrical nerve stimulation device, taken from the frame of reference of FIG. 1;

FIG. 8 is a bottom view of the transcutaneous electrical nerve stimulation device, taken from the frame of reference of FIG. 1;

FIG. 9 is a bottom right perspective view of the transcutaneous electrical nerve stimulation device; and,

FIG. 10 is a bottom left perspective view of the transcutaneous electrical nerve stimulation device.
